UNITED STATES PATENT OFFICE

DANIEL F. BRADFORD AND GEORGE E. HAMPTON, OF PITTSBURGH, PENNSYLVANIA

GAME

Application filed March 27, 1929. Serial No. 350,278.

This invention relates to a game and particularly to a game which endeavors to simulate the processes of selection at a dog show, in its rules of play.

5 The objects and advantages of this game, aside from its purely fun-making character as a game, are educational insofar as they illustrate to a degree, the manner in which a dog show is conducted and further to stimulate interest on the part of the children playing the game in the different breeds of dogs, many of which are illustrated.

10 The game is played on a board which is sub-divided and colored as indicated in the accompanying drawing.

15 As is illustrated in the accompanying drawing, the play board 11 is sub-divided into four main sections A, B, C, and D, respectively, to accommodate from one to four 20 players as may be desired. At the center of the board is a metal arrow 12 rotatably supported on a pivot 13 which secures the arrow to the board. Two circular rings 14 and 15 concentric with the pivot 13, are sub-divided 25 into boxes. Those in the inner ring 14 are colored with the colors, red, blue, yellow and green as indicated in the drawing. Those in the outer ring are numbered 1 to 5 in the five spaces assigned to each main section.

30 In addition to the boxes or spaces in the rings 14 and 15 assigned to each main section, colored sections are located along diagonals 16, 17, 18 and 19 extending from the center rings towards the corners of the board. On either side of the respective diagonals are located segments 20, 21, 22, 23, 24, 25, 26 and 27.

35 Each main section of the board is further provided with a qualification sub-division 40 28, sub-divided into three rows, 29, 30, and 31 of different colors as indicated. The rows are further sub-divided into eight columns to provide eight spaces or boxes in each row.

45 In the corner blank spaces 32, 33, 34 and 35, between the qualification sub-divisions are located pictures of dogs of different types and breeds.

50 Small counters, 36, consisting of flat discs of metal or fibre, have names of different

breeds of dogs stamped thereon and these constitute the entries in the dog show.

In playing the game, each player starts with a predetermined number of entries, up to eight. Beginning for example, with player A, he places his entry as indicated by a counter 36 in the ring or space in front of his qualification sub-division and spins the arrow which represents the judge. The space on the inner ring 14 at which the head of the arrow points when it stops indicates the honor or disqualification given to that entry. If, for example, the arrow stops pointing to any blue space on the inner, that entry is awarded a blue ribbon and is placed in box 60 65 number 1 of the blue row 29, of the A player's qualification sub-division.

70 Player B then places his entry and spins the arrow, and then places his entry in his qualification sub-division, depending upon the honor awarded by the judge. Each player repeats the same process in turn.

75 If the arrow stops at any of the disqualification spaces, that entry is disqualified and is withdrawn from the game. The players continue around the board, each player playing one entry at a time until all of the counters or entries with which they have started the game have either been placed or disqualified.

80 In the second time around the board the entry is placed in the appropriate box in column 2 of the qualification sub-division, or withdrawn from the game, as the case may be, and in each subsequent round, each entry is placed in the corresponding column of the 85 player's qualification sub-division.

85 After all the dogs have been judged and placed or disqualified, that concludes the preliminary judging in the game. For the final judging, those entries which have been awarded blue ribbons are placed by each player in the spaces numbered from 1 to 5 in the outer ring 15, in his section of the board.

90 After the blue ribbon entries have been placed, the arrow is again spun by the player having the largest number of blue ribbons for his entries.

95 Assuming that four entries of player A, three entries of player B and two each for 100

players C and D have been awarded blue ribbons, the corresponding counters will then be placed in boxes 1, 2, 3 and 4 of the outer or final judging circle 15 for player A; the corresponding counters will also be placed in boxes 1, 2 and 3 of the outer or final judging circle for player B; and the corresponding counters will also be placed in boxes 1 and 2 for players C and D, and player A then spins the arrow or judge 12. If the arrow stops pointing towards any one of the four counters so placed, his choice entry in box number 1 will be awarded the title of "best dog" in the show and player A will then be entitled to as many points toward a championship as the total number of blue ribbon entries in the ring, which, in this case, will be four points for player A, plus the number entered by players B, C and D, or a total of 11 points.

If, however, the arrow stops anywhere else except pointing at any one of his four counters, player A receives no award and no points whatever towards a championship rating, but if it stops at one of the counters of the other players, they will receive one point for each blue ribbon entry in the circle 15.

The first player receiving 15 points wins a championship and the game.

As sometimes may be necessary, several games may have to be played before a championship is won, or may have for its goal the best dog in show as may be desired.

Although we have illustrated the board as having the selecting dial and arrow physically associated therewith, it will be obvious that the dial and selecting arrow may be made to constitute a separate unit for use with the board as otherwise laid out. Such arrangement offers certain advantages in the process of manufacturing.

Our invention is not limited to the specific layout as it is illustrated and colored, since the same may be variously modified without departing from the spirit and scope of the invention as set forth in the appended claims.

We claim as our invention:

1. A game simulating the selection processes of a dog show comprising a board of play subdivided into sections to accommodate one or more players, a plurality of counters to constitute dog entries, a judging section consisting of a dial with spaces having indicia indicating honors and disqualifications, and a rotatable arrow associated with the dial to be spun by each player for each entry to determine the award or disqualification of that entry.

2. A game simulating the selection processes of a dog show comprising a board of play subdivided into sections to accommodate one or more players, a plurality of counters to constitute dog entries, a judging section consisting of a dial with spaces having indicia indicating honors and disqualifications, and a rotatable arrow associated with the dial to be spun by each player for each entry to determine the award or disqualification of that entry.

tions, and a rotatable arrow associated with the dial to be spun by each player for each entry to determine the award or disqualification of that entry, a classification panel for each player's position subdivided and graded to receive each classified counter and indicate the relative standing of each player.

3. A game of the character described in claim 2, embodying a judging section provided with honor spaces for secondary judging of the entries awarded honors and positioned on the classification panels.

4. A game of the character described comprising a board of play subdivided into four sections to accommodate up to four players, a judging ring consisting of marked circumferential spaces indicating honors and disqualifications, a rotatable arrow to be spun by each player to indicate the honor or disqualification to be accorded an entry according to the marking of the indicated space, and a plurality of secondary marked spaces for indicating with the arrow a second or final judging of the qualifying entries, and a plurality of counters for each player, to represent the dog entries in the show.

In testimony whereof, we have hereunto subscribed our names this 6th day of March, 1929.

DANIEL F. BRADFORD.
GEORGE E. HAMPTON.
